UNITED STATES PATENT OFFICE

1,946,713

CABLE TERMINAL

Charles A. Rowley, East Orange, N. J.

Application January 22, 1932. Serial No. 588,043

1 Claim. (Cl. 173—269)

This invention relates to terminals for cables and more particularly to means for facilitating the attaching of such terminals to cables.

Terminals of the type herein described are widely used on cables, for example, in the ignition systems of automobiles. Heretofore, it has been the practice to crimp the terminal on to the end of a cable by employing a tool especially designed for such a purpose; and the use of a special tool is objectionable for there are many situations requiring the attaching of terminals when the tool is not available.

It is, therefore, an object of this invention to provide a terminal which is simple in construction and which may be readily attached to cables without necessitating the use of a special tool.

A further object is the provision of a terminal having a section which may be depressed to hold the terminal firmly on a cable.

20 These and other advantageous objects, which will later appear, are accomplished by the simple and practical construction and arrangement of parts hereinafter described and exhibited in the accompanying drawing, forming part hereof, and in which:

Figure 1 is a perspective view of one form of my invention.

Figure 2 is another perspective view of the form shown in Figure 1.

30 Figure 3 is a perspective view of a blank from which the terminal shown in Figures 1 and 2, is made.

Figures 4 and 5 are perspective views of another form of the invention.

35 Figure 5a is a perspective view of an insulator used in connection with the terminal shown in Figures 4 and 5.

Figure 6 is a perspective of the terminal assembled with the insulator.

40 Referring to the drawing, in Figure 3 is shown a blank 18 having at one extremity an aperture 19, and intermediate its length notches 20 on opposite edges. At the opposite extremity the blank has a pair of projections 21 adapted to enter the notches 20 when the blank is bent to form a cylindrical member 15 as shown in Figure 2. The blank is also slotted to provide a narrow strip 22. In Figure 1 is shown a cable 16 having a portion 17 of the wire exposed and bent over the end 50 of the cable. A terminal made from a blank 18 is placed over the end of the cable and contacts the exposed wire 17, the section 22 being forced into the fabric of the cable by means of any convenient tool to securely hold the terminal in place.

55 In Figures 4 and 5 is shown a terminal having

a fork 31, which is integral with the cylindrical portion 32, which has a portion 34 forced into the cable to firmly hold the terminal thereon. In Figure 6 is shown the terminal and cable 33 assembled with an insulator 35, as shown in Figure 5a.

It will be seen that in the several modifications disclosed, the terminals are held on the cables by the depressed sections biting into the fabric of the cable, and obviously no special tool is necessary to force the portions 22 or 34, into the fabric. As a result, the terminals described herein may be readily attached to cables in any situation, as there is always convenient some instrument, such as a nail, screw driver, or the like, by means of which the portions 22 or 34, may be forced into the fabric to hold the terminals securely on the cables.

The connectors are of such shape as to lend themselves readily to manufacture by the use of suitable punches and dies from ordinary sheet metal, preferably brass.

The foregoing disclosure is to be regarded as descriptive and illustrative only, and not as restrictive or limitative of the invention, of which obviously an embodiment may be constructed, including many modifications without departing from the general scope herein indicated and denoted in the appended claim.

Having thus described my invention what I claim as new and desire to secure by Letters Patent, is:

A device for making a cable terminal comprising a flat substantially rectangular metal sheet having an aperture at one end and a pair of spaced projections at the other end, said sheet having a notch in each of its side edges to receive said projections, said sheet having two spaced parallel slits to provide a section which may be readily forced out of the plane of the sheet.

CHARLES A. ROWLEY.
